CAR CONSTRUCTION

John O. Neikirk, Chicago, Ill., assignor to Rodger
Ballast Car Company, Chicago, Ill., a corpora-
tion of Maine

Application January 10, 1931. Serial No. 507,773

7 Claims. (Cl. 105—259)

This invention relates to an improved construction for railroad cars of the type employing a plow which is drawn longitudinally through a plurality of cars for discharging the lading laterally from the car through openings provided by hinged or door-like side walls.

It is an object of this invention to provide a car construction which is adapted for use with discharging plows of usual and standard construction and dimension and yet to provide additional space or carrying capacity throughout the body of the car.

It is a further object of this invention to provide certain novel and improved features of construction whereby a better and stronger car is produced including simple and efficient lateral guide means for the plow.

It is a further object of this invention to provide a car of the above described type in which guide means are provided for the plow which not only serve well in service for guiding the plow but also enter into the construction of the car to produce a stronger and more durable structure.

It is a further object of the present invention to provide certain improved structural features such as sloping discharge surfaces and associated parts wherein the principles of the present invention may be embodied in an efficient and practical construction which is relatively simple as to form and inexpensive to manufacture and maintain.

These and other objects not specifically enumerated are contemplated for the present invention as will hereinafter more readily appear to one skilled in the art as the following description proceeds.

The disclosure herein given is merely for the purpose of illustration and is not to be considered as limiting the invention in any respect as the scope of the invention should be determined from an understanding of the present disclosure and an appreciation of the advantages which the invention produces therein.

The following description may be more readily understood by referring to the accompanying drawing in which:

Figure 1 is an elevational transverse view in cross section, of a railroad car constructed in accordance with the present invention;

Figure 2 is a view taken on the line 2—2 of Figure 1 and looking in the direction of the arrows;

Figure 3 is an enlarged perspective view of the combined plow-guide and bracing piece employed in the illustrated form of the present invention.

Before proceeding with the detailed description of the present disclosure, it will assist in understanding the present invention to realize that a large number of cars of this type are now employed in commercial practice. These cars have utility in various uses, for instance, the conveyance of tree stumps, or other large and bulky ladings possessing irregular shape, and not requiring special or careful handling in loading and unloading operations.

These cars, as a type, have been used with good success for a long period of years and practice has shown that the life of plows used for unloading the cars exceeds that of cars subjected to substantially the same use. The result has been that the replacement of cars from time to time has involved the necessity of accommodating the construction of the car to use with old plows already possessed by the users, as economy has demanded that the full life of the plows be availed of.

As time has passed, the replacement of cars and plows has consistently involved a consideration of adapting the plows to the cars on hand and the cars to the plows on hand and consequently it is still a matter of extreme importance to provide a car construction which is capable of use with a standard and old type of plow. A peculiarity arises in the fact that cars as originally built were of less width than those now in demand and consequently the problem which is now present and which is solved by the present invention is that of increasing the capacity of the cars in accordance with modern demand without sacrificing the advantage of utilizing the standard and narrow gaged plow.

With these considerations in mind, the construction of the disclosed car will be described.

By referring to the drawing, it will be noted that the present invention is illustrated as embodied in a car having a suitable under carriage 10, supported on wheels 11 which are in turn mounted on the track rails 12. The under carriage embodies in its construction, center sill members 13 and side sill members 14. These are shown as composite parts made up in channel formation but it is obvious that any suitable construction may be employed.

As shown in Figure 1, the present embodiment of the invention comprises longitudinal channel irons 15, which are spaced inwardly from the side edges of the car and supported on the under carriage construction 10. Angle supports 16, secured by rivets 17 are carried by the channel irons 15 and together constitute side supports for

the floor 18, disposed centrally of the car. In the illustrated form, the flooring is also supported on the element 19 which is carried on the upper edges of the center sills 13.

5 The side sills 14 are illustrated as supported from the under carriage 10, by means of brackets 20, secured by suitable rivets 21 to the outer ends of the under carriage. Extending upwardly from the center sills are side stakes 22 which are 10 preferably formed in the manner shown in Figure 2.

Here it will be noted the side stake 22 comprises two angle pieces placed together and held by suitable means such as rivets 23. The side stakes 15 are strengthened by means of the diagonal brace 24, which extends diagonally upwardly and outwardly from the under carriage 10 to the side stakes, the brace extending between the two angle pieces constituting the side stake and there 20 held by suitable means, such as rivets 25.

In addition to the brace 24, increased strength is provided for the side stakes by means of the bracket 26 which is preferably formed as two pieces as shown in Figure 2, and has one end 25 riveted to the upper flange of the channel iron 15 and the other end riveted to the brace 24.

The guide piece 27, better shown in Figure 3, is mounted on top of brackets 26 with its lower flange 28 riveted thereto and with its upper 30 flange 29 secured by rivets between the angles constituting the side stakes.

From this combination of parts, it will readily appear that the side stakes are securely braced and in addition, the guide pieces 27 are positioned 35 in a manner to engage the lower edges of the plow 30, for guiding its course of movement longitudinally of the car.

Shedding surfaces 31 are also provided which extend from the upper flange of the angle iron 40 15 to the upper edge of the side sills 14, the two edges thereof being secured by some suitable means such as rivets. These shedding surfaces extend throughout the length of the car and provide inclines between the side stakes for assisting 45 the action of the plow in discharging the lading from the car.

In addition to the above described elements, side walls 32 are provided in the nature of doors which are pivoted at their upper ends as at 33, 50 so as to swing freely outwardly to entirely displace the side walls and thereby permit the lateral discharge of lading.

For the purpose of strengthening the construction an upper chord 34 is preferably provided 55 for tying the upper ends of the side stakes. The doors or side walls may be of any suitable construction but are herein illustrated as being formed of wooden boards having bracing members 35 extending downwardly with their lower 60 ends 36 constructed for cooperation with the door locking mechanism 37.

It is important to observe in this construction that the flooring 18 disposed centrally of the car has its upper surface slightly below the plane 65 of the upper surface of the channel irons 15 so that in practice, the channel irons constitute what may be considered a track for the plow.

Furthermore, the lower flanges 28, on the guide pieces 27, are disposed in the same horizontal 70 plane as the upper edges of the channel so that the lower corners of the plow may engage therewith in its discharging travel through the car.

The result of this construction is that strong and durable means are provided for lateral contact 75 with the lower edges of the plow whereby

the plow is maintained against lateral displacement and is guided in its discharging travel. Not only this, but the guiding pieces serve to take up the space between the plow and the side walls so that the side walls in the present construction may be moved outwardly so as to increase the capacity of the car, without requiring a modified wider type of plow. 80

A car of this construction is provided with side walls and are spaced a greater amount than 85 cars of a similar nature prior to this invention.

In addition, the guiding pieces serve as an element in the bracing structure whereby unusual strength and durability is given to the side stakes and to the car construction proper. 90 The sloping floors or shedding surfaces referred to extend inwardly to a point adjacent the channels so that the plow, at its broadest portion, over-hangs to some extent, whereby the discharging operation is greatly assisted. 95

The construction also provides the upper surfaces of the angle irons 15 which serve in the nature of a track way for supporting the weight and taking the frictional sliding wear of the plow in its movement through the cars. 100

It will be observed that the present invention results in a car construction which is simple in formation and inexpensive to manufacture and maintain and yet one which is durable and strong in service. 105

The car of the present invention provides an increased capacity and yet is capable of use with the old and standard type of plows.

I claim:

1. A railroad car of the character described 110 having a car body comprising an under frame, side stakes attached to the edges of said under frame and longitudinal beams supported on said under frame and spaced inwardly from said side stakes, bracing means extending between said 115 beams and side stakes and a guide piece for a lading discharge plow having a plow contact surface spaced inwardly a substantial distance from the inner surface of said side stakes and attached to said side stakes and bracing means 120 and occupying the corner space between said side stakes and said bracing means.

2. A railroad car of the character described 125 having a car body comprising an under frame, side stakes attached to the edges of said under frame, longitudinal beams supported on said under frame and spaced inwardly from said side stakes, bracing means extending between said 130 beams and side stakes and guide elements attached to said side stakes and bracing means 135 occupying the corner space between said side stakes and said bracing means and a lading discharging plow for said car of less width by a substantial amount than the distance between opposite side stakes and adapted for guiding engagement with said guide elements.

3. A railroad car of the character described comprising an under frame, side stakes attached to the edges of said under frame and longitudinal beams supported on said under frame and spaced inwardly from said side stakes, a floor for said car supported between said beams and bracing means extending between said beams and said side stakes, comprising guide elements adapted for guiding engagement with the lower 140 edges of a lading discharging plow and having plow contacting surfaces spaced inwardly a substantial distance of the car from said side stakes. 145

4. A railroad car of the character described comprising an under frame, side stakes attached 150

- to the edges of said under frame, and longitudinal beams supported on said under frame and spaced inwardly from said side stakes, a floor for said car supported between said beams, shedding surfaces extending between said beams and the outside edges of said car and bracing means attached between said beams and side stakes comprising a guide piece adapted for guiding engagement with the lower edges of a lading discharging plow and having its plow contacting surface spaced inwardly a substantial distance of the car from said side stakes. 5
5. A car of the character described comprising an under frame and side stakes attached at the side edges of said under frame, longitudinal beams supported on said under frame and a floor for said car comprising a horizontal portion between said beams and sloping portions between said beams and the outer edges of said car, a lading discharging plow for said car of greater width than the horizontal portion of said floor but of less width by a substantial amount than the distance between opposite side stakes and means for guiding engagement with the lower edges of 10 said plow attached to said side stakes and occupying the space between said side stakes and said plow. 10
6. A car of the character described comprising an under frame and side stakes and bracing means extending between said side stakes and under frame, longitudinal beams supported on said under frame, spaced inwardly from said side stakes and other bracing means extending between said beams and first named bracing means, and guide elements attached to said side stakes and other bracing means and occupying the corner space therebetween. 15
7. A car of the character described comprising an under frame and side stakes and bracing means extending between said side stakes and under frame, longitudinal beams supported on said under frame, spaced inwardly from said side stakes and other bracing means extending between said beams and first named bracing means, and guide elements attached to said side stakes and other bracing means and occupying the corner space therebetween and sloping shedding surfaces extending between said beams and the outer edges of said under frame. 20
